SIGNAL SYSTEM WITH SIGN AND ALTERNATING FLASHING LAMPS

Irwin M. Hart, Lorain, Ohio, assignor to The Winko-Matic Signal Company, Lorain, Ohio

Application May 15, 1951, Serial No. 226,356

1 Claim. (Cl. 340—83)

1

This invention relates to road-side traffic signs and particularly to an activated warning sign.

Conducive to a better understanding of this invention, it may be well to point out that road-side signs bearing information for the guidance and safe operation of vehicles using the highway have long been used. Such signs are usually made of sheet metal and bear indicia on the face thereof conveying information as to the nature of the road ahead such as—"Curve"—"Hill"—"Railroad crossing"—"Dead end" etc. Other signs convey orders as to the manner of operating the vehicle such as—"Slow"—"Stop"—"20 mile zone" etc. Over the years such signs have become standardized and the motorist has come to be relatively oblivious of them. Furthermore, such still signs are not readable until the motorist is relatively close and, unless he is looking directly at them, are usually passed by unnoticed.

The obedience of a motorist to a warning sign is in direct proportion to the visibility and attention value of the sign.

The attention getting value of a flashing light and especially the combination of two synchronized alternately flashing lights has long been appreciated by the railroads, which use such a device to mark their highway crossings.

The primary object of this invention, therefore, is to provide a road-side traffic warning sign that has action and movement in the form of alternating light flashes that instantly draw attention to the sign, both day and night under adverse as well as good weather conditions.

Another object is to provide an action device that can be easily combined with any existing road-side warning sign at a minimum cost of time and money.

Still other objects are to provide a device of the type described that is relatively inexpensive to manufacture, rugged in construction and reliable in operation.

These and other objects of the invention will become apparent from a reading of the following specification and claims, together with the accompanying drawing wherein like parts are referred to and indicated by like reference characters and wherein:

Figure 1 is a perspective view of the activated road-side warning sign, which is the subject of this invention, showing the flasher and indicia bearing members separated and with the flasher member housing partly broken away to disclose the inner construction thereof;

2

Figure 2 is a front elevation of the device as it appears mounted on a road-side pole or stanchion;

Figure 3 is a rear elevation of the signal-light and motor panel; and

Figure 4 is a top plan view of the device showing the housing cover in its open position.

Figure 5 is a schematic layout of the electric flasher system for alternately energizing the incandescent lamps of the device.

Referring more particularly to the drawing, reference numeral 10 indicates a weather-tight sheet metal housing having a hinged cover 13. The housing 10 has two vertically spaced bull's-eye lenses 18 and 19 mounted in the front wall thereof, as shown in the Figure 1. A louvered air intake opening 12 is located at the lower end of the housing side wall and two louvered heat vents 11 are located on the front wall between the bull's-eye lenses 18 and 19. Two facing vertically extending metal channels 29 are mounted on the inner side walls, spaced rearwardly of the front wall, as shown in the Figures 1 and 4. Laterally extending semi-circular brackets 14 and 15 mounted on the front wall above each bull's-eye lens serve as supports for the herein-after described indicia bearing member and also as shades for the lenses against outside light.

A rigid sheet metal panel 25 having flanged edges 26 is slidably mounted between the two channels 29. Two openings 27 and 28 are cut in the panel. These openings are spaced similarly to the spacing of the lenses 18 and 19 and are aligned with the lenses when the panel is in place.

Incandescent electric lamps 21 and 22 are mounted on the panel behind each of the openings 27 and 28 respectively. The light source of each lamp being aligned with the optical axis of its associated bull's-eye lens. The preferred type of lamp is the regular so-called 60 watt traffic bulb, although other wattages may be used to suit particular conditions.

Reference numeral 20 indicates a package unit containing an electric-motor-operated two position switch that alternately closes the circuit to each incandescent lamp 21 and 22. This unit is of the conventional type readily available to the public and includes means for varying the time interval between the alternate closing and opening of the two circuits which in turn determines the time between flashes.

A schematic layout of a typical unit of the type indicated is seen in the Figure 5. Reference numeral 40 indicates an electro-conductive drum,

made of brass or other suitable metal, mounted on the shaft 48 of a fractional horsepower motor 46 having a speed reducing gear system enclosed in its case so that the speed of rotation of its shaft 48 is reduced to between 60 and 120 R. P. M. The speed of the motor may be further controlled by the variable resistance 47. The drum 40 has an insulating insert 41 covering one-half of its surface. A flexible contact 45 carries current to a slip ring 44 on the drum to make the drum a part of one side of the electric circuit of the plug 23. The other side of the circuit being connected to the two incandescent lamps 21 and 22. Flexible contacts 42 and 43, electrically connected to the lamps 21 and 22, respectively, ride on the periphery of the drum 40, alternately contacting the insulated segment 41 thereof, as the drum rotates. The electric circuit to the lamps being completed when the contacts ride on the metallic surface of the drum and being interrupted when the contacts ride on the insulated segment 41. Thus the lamps 21 and 22 are alternately illuminated, the length of the illuminated and dark periods being determined by the speed of rotation of the drum 40.

The panel 25, with the flasher bulbs and switching mechanism mounted thereon, is slid into the housing 10 by fitting its edge flanges 26 between the channels 29 as shown in the Figures 1 and 4. This leaves a space 17 between the panel and the front wall of the housing which acts as a flue for air entering the louvered opening 12 which is warmed by the heat generated by the operation of the incandescent lamps 21 and 22 and the electric motor of the flasher switch contained in the package 20. The warmed air rises in the flue 17 and passes out through the vents 11.

A socket 24 to which the outside feeder line 16 is attached is mounted on the inside of the housing. The plug 23 of the flasher circuit is screwed into the socket 24 after the panel 25 is in place. Thus the panel 25 can be removed from the housing 10, if desired, after the plug 23 is unscrewed from the socket 24, without disturbing the weather-tight electrical connection through the wall of the housing.

Reference numeral 30 indicates a conventional sheet metal traffic warning sign bearing indicia 31 on the face thereof. The sign 30 may be newly manufactured for the particular assembly or it may be an existing sign that is easily converted to this novel use by boring two holes 32 and 33 therethrough, one being above the indicia 31 and the other below it. The spacing of the holes 32 and 33 is made similar to that of the lenses 18 and 19 and the diameter of the holes matches that of the semi-circular brackets 14 and 15. The sign 30 is mounted on the front wall of the housing 10 over the heat vents 11 by slipping the brackets 14 and 15 through the holes 32 and 33 respectively, as shown in the Figures 1 and 4. The openings 32 and 33 are aligned with the lenses 18 and 19 so that the lenses are visible through the openings 32 and 33 when the sign 30 is mounted on the housing 10, as described. The sign 30, so supported and located by the brackets 14 and 15, which interfit the upper edges of the holes 32 and 33, is further secured to the housing 10 by bolts or other suitable fastening means.

The entire assembly is then mounted on a road-side pole 34 facing on-coming traffic, as illustrated in the Figure 2. The alternate flashing of the incandescent lamps 21 and 22 causes

the bull's-eye lenses 18 and 19 to be alternately illuminated. Due to the so-called "persistence of vision" phenomenon of the human eye, this creates the illusion of a vertically swinging line of light that instantly attracts attention to the warning sign. The metal sign 30 is warmed by the heat escaping from vents 11. This prevents the accumulation of sleet and ice on the face of the sign, which often makes the conventional sign useless during stormy weather when the need for it is the greatest.

The activated warning sign just described is visible at least a mile away so that it is impossible for the most inattentive driver to avoid noticing it.

The unit is self contained, requiring no skilled labor in its installation and maintenance. In the event of mechanical or electrical failure, the panel 25 bearing all the flashing mechanism can be easily and quickly replaced by a new unit without the use of any tools whatsoever. The expense of installing activated warning signs is greatly reduced by the fact that existing still signs can be converted to this improved form by merely boring two holes on either side of the indicia thereon, whose spacing and diameter match that of the lenses 18 and 19 and the bracket supports 14 and 15.

In locations where it is desired to control traffic in two directions, it is possible to do so with a single unit by boring spaced holes in the rear wall of the housing 10 in alignment with the electric lamps 21 and 22. Bull's-eye lenses similar to those identified by reference numerals 18 and 19 are mounted in said spaced holes, together with a second pair of brackets. A second sheet metal sign having properly spaced holes is then mounted on the rear wall, facing on-coming traffic in the opposite direction to that faced by the warning sign 30.

It will now be clear that there has been provided a device that accomplishes the objectives heretofore set forth. While the invention has been disclosed in its preferred form, it is to be understood that the specific embodiment thereof as described and illustrated herein is not to be considered in a limited sense as there may be other forms or modifications of the invention which should also be construed to come within the scope of the appended claim.

I claim:

A traffic sign, comprising in combination, a flasher member including a weather-tight sheet metal housing having front, rear, top, bottom and side walls and also having two spaced bull's-eye lenses mounted in the front wall thereof and a heat vent positioned therebetween, a baffle plate mounted within the said housing spaced rearwardly of said front wall and forming therewith a flue, the said plate having holes therethrough aligned with each of said lenses, for the passage of light and heat, the said housing also having air inlets positioned in the side walls between the baffle and the rear wall near the bottom thereof, incandescent lamps mounted behind the baffle plate in alignment with each of the baffle holes and the optical axis of its associated bull's-eye lens, means within the housing for alternately energizing each of said incandescent lamps momentarily, and a conventional sheet metal road-side warning sign having traffic guiding indicia on the face thereof, the said sign having openings therethrough on either side of said indicia spaced the same as the signal lenses, the said sign member being mounted on the front

wall of the housing over the said heat vent with its spaced openings aligned with the signal lenses, whereby the alternately illuminated signal lenses are visible through the warning sign openings, and the heat created by the incandescent lamps serves to heat air entering the inlet to generate convection currents which pass through the baffle holes and flue and out the vent to warm the sheet metal sign, thereby preventing the accumulation of sleet and snow thereon during the 10 winter season.
